CLAIM

The ornamental design for a projector light source or similar article, substantially as shown and described.

DESCRIPTION

FIG. 1 is a perspective view from the front, upper right corner of the projector light source, with its rear support member in its extended position, showing our new design;

FIG. 2 is a perspective view from the rear, lower left corner thereof with its rear support member in its extended position and showing the other sides thereof; FIG. 3 is a perspective view from the front, upper left corner thereof with the support member in its retracted position; and

FIG. 4 is a perspective view from the rear, lower left corner thereof with the support member in its retracted position.

The broken line in FIGS. 1 and 2 shows a hand-held viewer, with which the new design may be associated and which does not constitute part of our new design.

FIG. 1

FIG. 2

FIG. 3

FIG.4
